ABSTRACT: An electron gun for a cathode-ray tube has a cathode centrally mounted in a ceramic ring. The ring has a metal holder comprising a flat plate with means extending about the periphery of the ring and forming a clamp against the other side. The cathode assembly is held in the electron gun assembly by embedding the edges of a flat plate extending from the ring into a pair of glass beads. The cathode is critically spaced from a grid comprising a flat apertured plate by having edges of the plate embedded in the same glass beads.

INVENTOR
HORST H. BLUMENBERG

BY Laurence R. Brown ATTORNEY

HOLDER AND MOUNTING MEANS FOR CERAMIC CRT CATHODE RING

This invention relates to electron guns for cathode-ray tubes and more particularly it relates to means for mounting and holding cathodes in electron gun arrays.

Special structures for mounting cathodes and first grid assemblies in cathode-ray tubes have been developed in the prior art to retain critical spacing and centering relationships. The more conventional of such structures finding widespread current use comprises a cuplike grid assembly with a retainer holding a ceramic ring in which the cathode is mounted inside the cup body. This structure as other known cathode mounting structures is expensive because the cup must be deep drawn and the interfitting parts must be formed to very close tolerances.

Other mounting techniques have been proposed to reduce cost while retaining precise dimensional stability such as that in the copending application of Horst H. Blumenberg and John Midkiff and entitled "Cathode Mount in Single Gun Indicia Tube," sn 843,316 filed July 22, 1969, and assigned to the assignee of this application. Therein the cathode extends from and is conductively connected to a flat metallic plate embedded at opposite ends in the two glass beads which hold the various electron gun electrodes in position.

It is well recognized however that a critical relationship of cathode and grid parts is necessary in many electron guns to maintain the necessary operability characteristics with the elevated cathode temperatures that tend to cause attendant changes of position because of thermal expansion and changes in emission because of generation of heat pockets. Thus careful control of thermal dissipation paths and relative positioning and shaping of parts is required with special metals for controlled expansion with heat or controlled conductivity of heat.

It is therefore an object of this invention to provide an operable structure affording acceptable performance under critical CRT conditions which is simple and inexpensive in structure and is operable without significant problems of variable emission, changing position of parts or requisite careful control of thermal conductivity.

It has been found in accordance with the invention therefore that a simple inexpensive holding and mounting arrangement for the cathode assembly in a CRT electron gun array can be provided with little criticality or variation in performance even when subjected to very stringent spacing and performance specifications necessary in miniature tubes. Such a mount has as a feature a cathode held in a ceramic ring which has a holding means thereabout holding the ring adjacent a flat apertured plate which extends from the peripheral edge of the ring and is embedded in two opposed glass beads. The ring is held in a clamped position on the flat plate by a metallic structure clamped to the ring on the side opposite from the plate. This holder structure is electrically insulated from a first grid, which preferably comprises a flat apertured plate held in a pair of opposed glass beads by embedded edges of the grid plate.

A more detailed description of the electron gun structure afforded by this invention is set forth together with further features, objectives and advantages of the invention in the following specification wherein reference is made to the embodiments set forth in the accompanying drawing, in which:

FIG. 1 is a perspective view of a cathode, disc and holder assembly afforded by this invention,

FIG. 2 is a plan view of a holder plate assembly,

FIG. 3 is an elevation view, partly in section, of a cathode-ray tube electrode assembly embodying the invention, and

FIG. 4 is a plan view assembly of a further embodiment of a cathode-disc-holder assembly afforded by the invention.

Now with reference to FIG. 1 a cathode assembly for a cathode ray tube (CRT) electron gun array is shown. This array comprises a ceramic ring 10 having a centrally located

cylindrical cup shaped cathode 11 with a planar emitting surface 12 (FIG. 3) disposed in a plane generally parallel to one passed through the body of the ceramic ring 10. The cathode 11 passes through an aperture in the center of ceramic disc 10.

5 The cathode assembly is provided with a flat plate mounting means 14 which extends away from the ceramic disc 10 so that opposite ends 13, 13' may be embedded in opposed glass beads 17, 18. For the purpose of providing a firm support to hold the cathode in a fixed known position in the electron gun, the ends may have notches 19, 20 therein.

A holder assembly 15 extends about the outer peripheral surface of ceramic disc 10 from one side to terminate in clamping means contiguous to the disc 10 on the opposite side. In the embodiment shown in FIGS. 1 and 2, a separate apertured flat plate 21 has a set of integral tabs 16 extended therefrom which may be bent at regions 22 and 23 to extend about the outer periphery of the ring at region 24 and serve to clamp the ring in place with the portion 25 disposed on the upper surface 26 of the ceramic ring. With this particular embodiment the holder assembly 15 about the ceramic ring 10 can be prefitted on the ring and then welded on a separate flat mounting plate 14. Deep drawn or more expensive cuplike retainers are not necessary with this structure, and therefore it is preferred, although the holder assembly 15 could be manufactured in other ways such as by forming a cup to hold the disc 10 on one side and rolling over the lip as clamping means on the other side, or by having a pair of half-cups on either side of the disc welded together.

20 30 With this arrangement of a separate flat mounting plate 14 and disc holder assembly 15, the two pieces may be relatively positioned and welded together at a proper position for disposing the emitting surface 12 of the cathode along the axis of the CRT electron gun, to thereby give some degree of 35 freedom of selection of the cathode 10 position relative to the mounting plate 14 position.

If the latter degree of freedom is not necessary a single-piece structure may be used as shown in FIG. 4 wherein the mounting plate 44 itself serves also as the holder structure for 40 the ceramic disc 10 by means of tabs 16' that may be formed in and bent away from the planar surface of the mounting plate to achieve the relationship on the disc periphery and upper surface set forth in FIG. 1.

45 Since the cathode assembly must be critically spaced and oriented in the electron gun with respect to the first grid, its relationship in the CRT assembly pictured in FIG. 3 is important. The cathode surface 12 must have a precise spacing relative to the first grid 30, which is a flat apertured plate embedded at its end portions in the beads 17, 18. The use of the 50 flat plates 14 and 30 minimizes any chance for twisting and distortion of spacing or tube characteristics because of thermal reaction on bent or stressed areas in cuplike or other bent or shaped mountings and for this reason the flat plate mounting structures afforded by this invention are not only inexpensive to manufacture but provide improved operating characteristics.

55 In addition this structural arrangement permits simple inexpensive mounting pieces to be designed in a way that can provide any necessary degree of thermal heat conductivity through the ceramic disc 10 from the cathode 11, and prevents the "heat pocket" characteristics existing when a cuplike grid envelope the cathode assembly. Furthermore, the first grid 30 is not extended in the vicinity of the filament leads

60 65 31 (as a cup grid might be) where it may pick up noise or interference, and thus also presents a low interelectrode grid-cathode capacitance which contributes to superior high frequency signal characteristics. The cathode mounting plate 14 may be left electrically floating or may be connected to ground as a suitable potential level to gather stray electrons, etc.

70 75 With this structure the first grid 30 and the cathode may be held in a simple jig and embedded in the beads 17, 18 along with the second grid 38, the focus electrode 32, anode 33, deflection plates 34, 35, 36 and the snubber spring mounting

structure 37 in a precise interelectrode spacing and orientation relationship. This assembled relationship with the cathode mount structure afforded herein permits a miniature tube to be constructed with electrostatic deflection electrodes for meeting exacting dimensional and operational specifications. A typical size relationship of the tube illustrated is 3 inches in overall length of an envelope (not shown) having three-fourths of an inch diameter unflared cylindrical configuration terminating in a flat phosphor screen at the viewing end.

What I claim is:

1. An assembly for a cathode-ray tube electron gun array comprising in combination,
a ring of insulating material,
a cathode mounted centrally in said ring and presenting a planar emitting surface in a plane parallel to a plane passed through said ring,
a holder about said ring comprising an apertured plate located on one side of said ring having clamping means extended about the outer peripheral surface of said ring and disposed contiguously on the opposite side of said ring,
and means extending from said plate for mounting said cathode in a fixed position in said electron gun array.
2. The assembly defined in claim 1 wherein said cathode

comprises a closed cylindrical cup extending through said ring and said apertured plate.

3. The assembly defined in claim 1 wherein said integral clamping means comprise a plurality of separated tabs extending from said apertured plate and formed about said ring.
4. The assembly defined by claim 1 including, a first grid electrode, and insulating means spacing said grid from the planar surface of said cathode to electrically isolate said grid from said apertured plate.
- 10 5. The assembly defined by claim 4 wherein the insulating means spacing the grid comprises a pair of glass beads.
6. The assembly defined by claim 5 wherein said grid consists of a flat plate having a centrally located aperture with edges of said plate embedded in said glass beads.
- 15 7. The assembly defined by claim 5 wherein said means extending from said plate for mounting said cathode comprises plate like means extending in substantially a given plane with edges embedded in said glass beads.
8. The assembly defined by claim 1 wherein the holder about said ring has said clamping means integrally extending from a plate contiguously contacting said one side of said ring.
9. The assembly defined by claim 8 wherein the clamping means consists of a plurality of discrete tabs located about the periphery of said ring.
